FLUID PUMP

Joseph Paul Laird, Philadelphia, Pa., assignor to
The Wicaco Machine Corporation, Philadelphia, Pa., a corporation of Pennsylvania

Application January 30, 1935, Serial No. 4,903

7 Claims. (Cl. 103—126)

My invention relates to the art of pumping heavy oils and other relatively thick and viscous fluids.

In a gear pump having adjustment of the rate of pumping by axial movement of one of the gears to match a variable part of its face against a corresponding part of the face of the mating gear, one purpose is to provide an equalizing connection between the spaces at opposite ends of the adjustment movement so as to facilitate flow of leakage liquid between the two spaces while the axial adjustment is being made.

In the handling of heavy oils and like fluids which are pumped with difficulty, a further purpose is to increase the fluidity of the oil by the use of a primary pump in so close relation to a secondary pump by which it is to be delivered as to give little opportunity between for the oil to increase in viscosity.

A further purpose is to break up and diffuse and preferably at the same time raise the temperature of heavy oils and other oily viscous materials pumped by a primary pump so as to lower their viscosity and render them of substantially uniform viscosity when delivered to a secondary pump whose pumping action is thus made more nearly uniform.

A further purpose is to break up and diffuse a heavy substance or an accumulation in an oil or other fluid pumped by a primary pump, thereby breaking up the "set" of the material pumped, and to deliver it to a secondary pump before the material has had opportunity to again become "set".

A further purpose is to provide primary and secondary gear pumps in series in a single unit having the capacity of the first of the series pumps in excess of the normal capacity of the second and having the capacity of the second pump adjustable by axial movement of one of the gears.

A further purpose is to interconnect primary and secondary pumps within the same pumping unit, of which the primary pump is designed to have the larger pumping capacity and the secondary pump is adjustable for quantity pumped, so as to secure any desired pressure of delivery from the primary pump and variable rate of delivery from the second pump.

A further purpose is to provide a primary gear pump having capacity in excess of its pumping needs and having a short circuit connection about the pump providing leakage against a predetermined preferably adjustable resistance, to pump from it to a secondary gear pump

of smaller capacity and having adjustment of the capacity of the secondary pump by axial movement of one of the gears and to facilitate leakage between opposite ends of the movable gear of the secondary pump so as to permit easy shifting of the movable gear.

A further purpose is to provide primary and secondary gear pumps, one of them adjustable, within the same pumping unit, whereby conveniently and with a high degree of space economy pressure may be maintained between the two pumps, not only to supply the second pump with fluid from the first but to add the pressure from the primary to the pressure of the secondary, pump, making it possible to secure the desired pressure from the secondary pump at a low energy expenditure in the secondary pump.

A further purpose is to operate a two-stage gear pump with higher volumes pumped by the primary stage, and to continuously by-pass at a selected pressure any excess of liquid pumped by the primary pump back to the inlet side of the primary pump.

In a two-stage gear pump, a further purpose is to by-pass continuously at a predetermined pressure excess liquid pumped by the secondary stage back to the conduit connecting the stages, and, if necessary, from the conduit connecting the stages to the inlet of the primary stage.

The construction shown is a preferred construction only, selected because of its practicability and its excellence in illustration of the invention.

Figure 1 is a section through the axes of the pumps taken upon line 1—1 of Figure 2.

Figure 2 is a section upon line 2—2 of Figure 1.

Figure 3 is a fragmentary section corresponding generally to Figure 1 but upon a smaller scale than that of Figure 1 and showing a second form of the invention.

Figure 4 is a fragmentary section corresponding generally to Figure 2 but upon a smaller scale than that of Figure 2 and showing another form of the invention.

Where gear pumps are operated at a relatively high rate of speed, such, for example, as 1750 R. P. M., the tolerances or clearances between the gears and their surrounding casings may be relatively large, because the speed of operation is sufficient to make the leakage through these relatively large tolerances small enough to be considered negligible in ordinary operation. On the other hand, when pumps of this character are greatly reduced in speed, (as for example down to 200 R. P. M.) it is necessary to operate

the pumps at very much closer tolerances or clearances.

With the axially adjustable gear type of pump, where the adjustable gear unit is moved axially to engage a larger or smaller proportion of the gear faces of its mating gear for larger or smaller pumping capacities, the spaces which must be allowed at the ends of the gear unit to permit movement of the unit axially become much more tightly sealed than where larger clearances have been provided. These spaces soon fill up with leakage from the material pumped.

Whereas clearances suitable for high speed gear operation have permitted leakage oil from the end of the gear toward which adjustment is being made to flow out past the movable unit and into the space at the end of the gear unit from which movement is being made, allowing easy adjustment, this pressure flow from the space at one end of the movable gear unit to the space at the other end of the unit requires more and more pressure with the smaller tolerances necessary for lower speeds until with the tolerances which are desirable from other standpoints it becomes almost impossible to shift the gear without breakage. This difficulty is, of course, very much increased with increase in viscosity of the fluid pumped.

One feature of the invention is intended to relieve this difficulty in adjustment of the gear unit and others provide for primary pump supply under pressure for a gear pump secondary and for the breaking up and smoothing of the liquid to be pumped, where its character or its initial temperature have given it a "set" making it difficult to pump smoothly and evenly until this "set" has been broken up.

The casing 10 is preferably made up as shown of two generally flat front and back plates or faces 11, 12, secured by bolts 13 to an intervening block or body 14 within which the various gears are mounted. The casing accommodates a primary gear pump 15 and a secondary adjustable gear pump 16. The primary pump is made up of driving gear 17 keyed to drive shaft 18 and driven gear 19 keyed to shaft 20. The secondary adjustable gear pump is made up of drive gear 21 and driven (adjustable) gear 22.

For convenience of reference the material pumped will hereafter be referred to as oil.

The primary gear pump draws its oil through any suitable pipe 23 leading from a sump to the suction side of the primary pump at 24 and transmits the oil through passages 25, 26 and 27 to the secondary gear pump, by which it is pumped through passages 28 and 29 to any suitable point of discharge for use.

The shaft 18 is suitably driven as from a pulley 30.

The shaft 20 is keyed to a driving gear 31, one of a transmission train which connects and synchronizes the two pumps. Gear 31 meshes with an idler 32 mounted upon a pin 33 and the idler in turn drives a gear 34 which is keyed to a shaft 35. The shaft 35 is keyed to the driving gear 21 of the second (secondary) gear pump. The gear 21 meshes to different extents according to the adjustment with the axially adjustable driven gear 22 mounted upon or about rod 36 and may turn directly upon the rod or upon a bearing sleeve 37 carried by the rod, as preferred.

The gear 22 and its bearing (if it bear upon a sleeve rather than upon the rod) is shifted longitudinally as part of a unit comprising pistons 38 and 39, both pinned to the rod 36 and shiftable

with it. The piston 39 is arcuately recessed to correspond with and form a close fit with the outer surfaces of the teeth of gear 21 and correspondingly to fit the cylindrical surface 40 of a cylindrical collar 41 which fills in the block or body at this point. The collar is of the same diameter as the outside of the teeth of gear 21.

The two pistons and the pump gear 22 between them slide as a unit within a cylinder of uniform diameter, into which project at one end and from the side the surface of the collar 41 and the gear 21. The teeth of the gear 21 mesh to varying axial extents with the teeth of gear 22, as the adjustable unit is moved to the right (Figure 1) to cause deeper axial extent of meshing, and hence higher pumping capacity, or to the left (Figure 1) to reduce the extent of meshing and a lower pumping capacity.

The two pistons 38 and 39 are alike except for the cylindrical recess of the piston 39 to correspond with and pass over the teeth of gear 22. It will be noted that a portion of the cylindrical surface of collar 39 projects into the cylinder within which the pistons slide.

In any position of the two pistons between the ends of their stroke there will be cylinder end spaces 42 and 43 between the respective pistons and the ends 44 and 45 of the cylinder. Inevitably the oil which is being pumped will leak past the pistons 38 and 39 into the spaces 42 and 43 so that at any time during the operation of the pumps the spaces 42 and 43 can be assumed to be full of oil with corresponding interference with movement of the adjustable pump unit.

Movement of the unit in either direction must force the oil out of the space toward which the pistons are moving in order to make it possible to move the pistons, at the same time tending to cause a vacuum in the space at the opposite end of the movable unit. With relatively large tolerances the difficulty in moving the pistons has not been a serious one, as the tolerances permit the oil to be forced back through the same channels by which it reaches these spaces, but, with reduced speed of pump rotation and the consequent necessity for reduced tolerances, this difficulty of moving the pistons becomes so great as to be serious, threatening breakage of the parts.

In order to relieve from trapping of oil in spaces 42 and 43 a leakage passage 46 is provided, terminating preferably in recesses 47 sufficiently back of the line of the ends of the cylinders so as not to be closed when the pistons are in their extreme positions at either end of the stroke. This leakage passage need have but very small capacity, since oil will not pass through it except when the movable pump gear unit is being shifted axially and there will then be the pressure of the operating mechanism to shift the pistons and force leakage through from one space 42 or 43 to the other. On the other hand, since leakage through this passage 46 can do no harm at any time there is no objection to having the resistance to flow through the passage 46 low.

In order that the leakage through passage 46 may provide the entire oil transfer adjustment needed with longitudinal movement of the gear unit, the cross-sections perpendicular to the rod 36 must be equal in the spaces 42 and 43. This can be accomplished readily by making the rod 36 of such size that its cross-section equals the cross-section by which the cylindrical portion 40 of the collar 41 projects into the cylinder. Approximately equal cross sections are quite desirable and are contemplated.

The rod 36 is made axially adjustable by threading it at 48 into an adjustment wheel 49 rotatably supported at 50 in a bracket 51 secured to the rear plate of the pump at 52. The adjustment wheel 49 is threaded at 53 to receive a nut 54 which holds the wheel 49 in position on the bracket. The adjustment wheel 49 is toothed at 55 to engage a spring detent 56 secured at 57 to the bracket 51. The adjustment wheel 49 may be power driven if desired through engagement of a rack with the teeth of the adjustment wheel.

Instead of the passage 46 through the pump body, a passage may be provided through the interior parts between the spaces 42 and 43. In Figure 3 I show a passage 46' through the rod 36, and equalizing pressure between the spaces 42 and 43.

The rod 36 is protected and may be in part supported by a gland 58 compressing packing 59 where the rod passes through the casing face 12. The driving shaft 18 is also protected by a gland shown at 60, compressing packing 61. It has outboard bearing at 62 and 63 in the face 11 of the casing and in the body 14. Pin 20 has bearing at 64 in the front face, at 65 in the body and at 66 in the rear face.

The bearing of the pin 35 is at 69 in the body and at 70 in the rear face; also at 71 in the collar 41 which in turn is supported at 72 within the body and within the face plate 11. The bearings 62, 63, 64, 66, 67, 68, 10 and 11 are all outboard bearings, an important feature in the construction of the device, so that the driving shaft and all of the pins are provided with outboard support.

The primary pump is shown as of greater capacity than the secondary pump in order that there may be a full supply of fluid for the secondary pump and preferably also in order that the secondary pump supply may be under pressure so as to increase the pressure of the discharge from the secondary pump.

In order that the primary pump may operate continuously, an overflow is provided between the primary and secondary pumps which overflow is preferably against an adjustable resistance. Two types of overflow are shown, the one through passages 73, 74 and 75 about the pump (Figure 2), protected by an adjustable ball check valve 76 whose pressure is applied by a spring 77 bearing against a seat 78 and adjustable by use of different springs and different positions of the plug 79; and the other through a pipe 80 (Figure 4) to a pressure tank, not shown. The pipe 80 may lead through a check valve to the sump side of the pump, as in the other case, or to a pressure tank in which the mounting pressures check the pumping effect of the primary pump.

The various passages about the pump are closed by plugs 81.

The secondary pump has a by-pass relief similar to that of the primary pump and comprising passages 73', 74' and 75', a ball check valve 76', spring 77' (which is desirably heavier than spring 77), valve seat 78' and plug 79'. Relief is thus provided against excessive pressure on the delivery side of the secondary pump.

In operation the pumping effect of the secondary pump is adjusted by longitudinal movement of the movable gear to mesh variably according to the position of the unit with the driving gear of the secondary pumping pair. This alone is broadly old.

When the secondary gear adjustment is to be effected the fluid pumped is driven from one

space 42 to the opposite 43 or vice versa, allowing free and easy movement of the secondary unit parts.

The operation of over-pumping by the primary as compared with the secondary will be determined in large measure by the extent of interfitting of the gears of the secondary pair. With adjustment of this secondary pair position fluid in one or other of the spaces 42 and 43 is driven to the other space, allowing free and easy adjustment of the position of the movable gear unit by operation of the adjusting wheel 49.

My novel pump finds wide application in the handling of various liquids, particularly liquids of high viscosity such as oils and chemicals, for example, viscose liquors. Particularly in handling liquids of this type the feature of equalizing pressure between two ends of the cylinder containing the movable gear is of considerable importance as is also the provision of pressure relief for the primary and secondary pumping stages. It is likewise desirable in this field to pump a relatively larger volume by the primary stage than that pumped by the secondary stage.

In view of my invention and disclosure, variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. A gear pump comprising front and back pump plates, a body between the plates, means for connecting the plates against the body protecting against leakage, a driving shaft, bearings therefor, a driving primary pump gear on the driving shaft, a primary pump driven shaft, bearings therefor, a driven pump gear upon said driven shaft and meshing with the driving pump gear, a driving transmission gear driven from said driven shaft, a driven transmission gear driven from the driving transmission gear, a shaft and bearings therefor, a driving secondary pump gear mounted upon the driven transmission shaft, a driven secondary pump gear adapted to mesh with and be adjusted axially with respect to the driving secondary pump gear, walls forming a cylinder fitting the driven secondary pump gear, pistons at opposite ends of the driven secondary pump gear, movable in the cylinder, one of them having an arcuate opening to accommodate the driving secondary pump gear, a filler for the arcuate opening, means for shifting the pistons and driven secondary pump gear longitudinally, walls forming an inlet to the primary pump, an outlet from the secondary pump and a series connection between the pumps, and the transmission gearing between the pumps being proportioned to operate the secondary pump at a higher speed than the primary pump.

2. A gear pump comprising front and back pump plates, a body between the plates, means for connecting the plates against the body protecting against leakage, a driving shaft, bearings therefor, a driving primary pump gear on the driving shaft, a primary pump driven shaft, bearings therefor, a driven pump gear upon said driven shaft and meshing with the driving pump gear, a driving transmission gear driven from said driven shaft, a driven transmission gear driven from the driving transmission gear, a

shaft and bearings therefor, a driving secondary pump gear mounted upon the driven transmission shaft, a driven secondary pump gear adapted to mesh with and be adjusted axially with respect 5 to the driving secondary pump gear, walls forming a cylinder fitting the driven secondary pump gear, pistons at opposite ends of the driven secondary pump gear, movable in the cylinder, one of them having an arcuate recess to accommodate 10 the driving secondary pump gear, a filler for the recess, a rod for shifting the pistons and driven secondary pump gear axially, the section of the rod and filler being approximately equal at the two ends of the cylinder, walls forming a passage 15 equalizing fluid pressures at the two ends of the cylinder, and walls forming an inlet and an outlet for fluid pumped and a fluid connection between the pumps.

3. A gear pump comprising front and back 20 pump plates, a body between the plates, means for connecting the plates against the body protecting against leakage, a driving shaft having bearing in the front plate and body, a driving primary gear on the driving shaft, a primary pump 25 driven shaft having bearings in the front plate and body, a driven pump gear upon the driven primary shaft and meshing with the driving primary gear, a driving transmission gear also upon the driven primary pump shaft, an idler shaft 30 having bearings in the rear plate and body, an idler thereon meshing with the driving transmission gear, a driven transmission gear shaft, a driven transmission gear shaft having 35 bearings in the rear plate and the body at opposite ends of the driven transmission gear, a driving secondary pump gear mounted upon the driven transmission shaft, a bearing for the driven transmission shaft between the secondary pump 40 gear and the front plate, a secondary driven pump gear adapted to be adjusted axially of the driving secondary pump gear, walls forming a cylinder within which the driven secondary pump gear moves, pistons at opposite ends of the 45 secondary driven gear movable in the cylinder, one of them having an arcuate recess to accommodate the driving secondary pump gear and sealed by the bearing member for the driven transmission gear shaft, means for shifting the 50 pistons and driven secondary pump gear longitudinally, walls forming a passage for equalizing fluid pressures at the two ends of the cylinder, walls forming an inlet to the primary pump and an outlet from the secondary pump and a series 55 connection between the pumps, the transmission gearing between the pumps operating the secondary pump at higher speed than the speed of the primary pump.

4. A gear pump comprising front and back 60 pump plates, a body between the plates, means for connecting the plates against the body protecting against leakage, a driving shaft having bearing in the front plate and body and packed within the front plate, a driving primary gear 65 on the driving shaft, a primary pump driven shaft having bearings in the front and rear plates, a driven pump gear upon the driven primary shaft and meshing with the driving primary gear, a driving transmission gear also upon the 70 driven primary pump shaft, an idler shaft having bearings in the rear plate and body, an idler thereon meshing with the driving transmission gear, a driven transmission gear shaft, a driven transmission gear thereon driven by the idler, 75 the driven transmission gear shaft having bear-

ings in the rear plate and the body at opposite ends of the driven transmission gear, a driving secondary pump gear mounted upon the driven transmission shaft, a bearing for the driven transmission shaft between the driving secondary pump gear and the front plate, a secondary driven pump gear adapted to be adjusted axially of the driving secondary pump gear, walls forming a cylinder within which the driven secondary gear moves, pistons at opposite ends of the secondary driven pump gear movable in the cylinder, one of them having an arcuate recess to accommodate the driving secondary pump gear and sealed longitudinally of the recess by the bearing member for the driven transmission gear shaft, means for shifting the pistons and driven secondary pump gear longitudinally, walls forming a by-pass from one end of the cylinder to the other, walls forming an inlet to the primary pump, an outlet from the secondary pump, fluid series connection between the pumps, and transmission gearing between the pumps operating the secondary pump at high speed with respect to the primary pump.

5. A casing, a primary pressure pump, a secondary gear pump having series fluid connections with the primary pump, one gear of which secondary pump is shiftable within a cylindrical space in the casing, and of smaller secondary pumping capacity than the capacity of the primary pressure pump, whereby a portion only of the fluid discharging from the primary pump is pumped by the secondary gear pump and the secondary gear pump is constantly supplied under pressure from the primary pump, means providing for the discharge of the over-supply of fluid, the structure being characterized by a shaft for longitudinally moving the shiftable gear within the cylindrical space, a shield adjacent the second secondary gear, pistons at opposite faces of 40 the shiftable gear fitting the walls of the cylindrical space, one of said pistons surrounding the shaft and the other of which pistons is cut away to pass over the secondary pump gear which is not shifted and to pass over the shield, to protect 45 against excessive leakage of liquid pumped into the ends of said space and walls forming a by-pass within the body of the casing of the pump between opposite ends of the cylindrical space whereby pressure of trapped fluid in the cylindrical space interfering with shifting of the gear of the pump is relieved and shifting is facilitated, the effective cross sectional areas of the shaft surrounded by the one piston and the cut-away part of the other piston being approximately 50 equal, whereby the total volume of the by-pass plus the portions of the said cylindrical space longitudinally beyond the pistons remains substantially the same at all positions of the shiftable gear.

6. A casing, a primary pressure gear pump, a secondary gear pump fed therefrom through series fluid connections between said pumps and of smaller pumping capacity than the capacity of the primary pressure pump whereby a portion only 65 of the fluid discharging from the primary pump is pumped by the secondary gear pump and the secondary gear pump is constantly supplied under pressure from the primary pump, one of the gears of the secondary pump being axially adjustable and the other of which gears is axially fixed, means providing for the discharge of an over-supply of fluid supplied to the secondary pump, the structure being characterized by walls forming a cylinder in the casing co-axial with and 70

- containing the adjustable gear of the secondary pump, a shaft for axially shifting the adjustable gear within said cylinder with respect to the fixed gear, a shield in line with the fixed gear and 5 extending into the cylinder from the side, pistons at opposite faces of the adjustable gear sealing against the walls of the cylinder, one piston surrounding the shaft and the other of which pistons is cut away to pass over the fixed gear 10 and seal against it and against the shield to protect against excessive leakage of the liquid pumped into the ends of the cylinder, and walls forming a by-pass between opposite ends of the cylinder whereby pressure of the trapped fluid 15 in the cylinder interfering with shifting of the gear of the pump is relieved and shifting is facilitated, the effective cross-sectional areas of the shaft surrounded by the one piston and the cut-away part of the second piston to seal with the shield being approximately equal whereby the 20 total volume of the by-pass and of the portions of the said cylinder space longitudinally beyond the pistons remains substantially the same in all positions of the adjustable gear.
- 25 7. In a gear pumping device, a casing, walls
- forming a cylinder therein, interconnecting gears which together form a secondary pumping element, one of which gears is fixed against axial movement and the other of which is axially movable in the cylinder, means for axially moving 5 said movable gear comprising a shield having a portion extending into the cylinder from its side at one end of the axially fixed gear, a piston connected with the axially movable gear and adapted to seal with the cylinder and having one side recessed and sealing against the shield, a second piston fitting the cylinder and a shaft upon which the pistons are mounted, passing through the casting and of cross-section approximately that of the recess in the first piston whereby the total 15 volume of the portions of the cylinder space axially beyond the two pistons is approximately the same irrespective of the adjusted position of the two pistons, the construction being provided with a by-pass from one end of the cylinder to the 20 other through a part fixed during normal operation whereby fluid is free to pass between the two ends of the cylinder and means for shifting said shaft.

JOSEPH PAUL LAIRD. 25
